United States Patent

Des. 237,090
Patented Oct. 7, 1975

237,090

EARPHONE

Haruo Yanagawa, Tokyo, Japan, assignor to Ashida
Onkyo Kabushiki Kaisha, Tokyo, Japan

Filed Oct. 16, 1973, Ser. No. 406,867

Term of patent 14 years

Int. Cl. D14—03

U.S. Cl. D26—14 H

FIG. 1

FIG. 2

FIG. 3

FIG. 4

FIG. 5

FIG. 6

FIG. 7

FIG. 1 is a front view of an earphone embodying my new design;

FIG. 2 is a top plan view thereof;

FIG. 3 is a bottom plan view thereof;

FIG. 4 is a left side elevational view thereof;

FIG. 5 is a right side elevational view thereof;

FIG. 6 is a side elevational view on line 1-1 thereof;

FIG. 7 is a perspective view thereof.

I claim:

The ornamental design for an earphone as shown.
